UNITED STATES PATENT OFFICE.

JAMES S. JOHNSTON, OF UTICA, NEW YORK, ASSIGNOR, BY DIRECT AND MESNE ASSIGNMENTS, TO JOHNSTON MANUFACTURING COMPANY, OF UTICA, NEW YORK, A CORPORATION OF NEW YORK.

COMBINATION SWITCH AND SAFETY-FUSE.

1,049,305.

Specification of Letters Patent. Patented Dec. 31, 1912.

Application filed March 12, 1908. Serial No. 420,575.

To all whom it may concern:

Be it known that I, JAMES S. JOHNSTON, of Utica, in the county of Oneida and State of New York, have invented certain new and useful Improvements in Combination Switches and Safety-Fuses; and I do hereby declare that the following is a full, clear, and exact description thereof, which will enable others skilled in the art to which it appertains to make and use the same, reference being had to the accompanying drawings, and to the letters of reference marked thereon, which form part of this specification.

The object of the invention is to provide an improved combined form of electrical switch and safety fuse, that is simple, efficient and well adapted to meet the requirements of such a device in a practicable and satisfactory manner.

The device embodies means whereby the fuse that has become spent or burned out may be readily replaced by a new one. Further the device permits of the observation of the fuse at all times.

Other objects will appear by reference to the drawings, in which:

Figure 1 illustrates a face view of a section of a switch board with a pair of my improved switches mounted thereon, and shown in open position, in connection with other accessories of the board. Fig. 2 illustrates a longitudinal section of one of the switch parts, in connection with a section of the board and other parts which are accessories thereto. Fig. 3 is a similar sectional view to Fig. 2, taken on a plane at right angles with the section of Fig. 2, the parts being shown in closed position. Fig. 4 is a transverse section taken on line 4—4 of Fig. 1. Fig. 5 is an enlarged detailed section of a modified form of construction. Fig. 6 is a face view of a section of switch board with a pair of switches of modified form of construction in position thereon. Fig. 7 is a longitudinal sectional view of one of the switch members as shown in Fig. 6 and in closed position. Fig. 8 is a transverse section taken on line 8—8 of Fig. 6. Fig. 9 is a detailed sectional view of a fuse and its mountings employed in the construction.

Referring to the reference letters and figures in a more particular description, 10 and 11 indicate the two parts of a tubular container, which telescope with reference to 55 each other, the former of brass or conducting metal and the latter preferably of glass and at least of non-conducting material. The part 10 is mounted to slide longitudinally in a spring clip 12. The part 11 is 60 formed with a metal cap 13 received in a spring clip 14, and the cap has an encircling enlargement 13^a received in the transverse slot of the clip 14, whereby it is held against longitudinal movement. The tubular containers are provided in pairs, secured together as to parts 10 for longitudinal movement by a cross bar 15 of insulating material, on which cross bar is provided a handle 16. The clips 12 are respectively electrically 70 connected with the bus bars 17 and 18, and the clips 14 are electrically connected with the two ends of a distributing circuit.

Within the capped ends of the part 11 is disposed a fuse wire 20, one end of which 75 is in electrical contact with the cap, and this fuse wire is further inclosed, largely for the purpose of support, in a tubular case 21. At each end the fuse wire will preferably be constructed with an enlargement 80 provided by twisting if desired, whereby the end becomes larger than the opening through the tubular case 21.

In the part 10 is provided a contact coil spring 22 supported on a stem 23 from the 85 head 24 closing the end of the part. When the parts 10 are moved away from the clips 14 into the positions shown in Figs. 1 and 2, the circuit is broken as between the end of the contact spring 22 and the end of the fuse 90 wire 20. When moved in the opposite direction and into the position as shown in Fig. 3, the circuit is established from the clip 12 through the body of the part 10, the head 24, the stem 23, and spring 22, the fuse 95 20, the caps 13, to the clip 14. In case the quantity of the current becomes excessive, the fuse 20 will burn or blow out in one or both branches of the circuit. In the event the fuses are blown out, or for any 100 other reason it becomes desirable, the switch with the fuses are readily removed by the

operator by means of the handle 16 withdrawing the pair of containers bodily from the face of the switch board, the same passing out from the spring clips 12 and 14. 5 When so removed the caps 13 can be removed and the fuses with their cases replaced by others. After being put in working order, the switch, as a whole, can be returned to its position on the switch board 10 either while in open or closed position by locating it properly with reference to the clips 13 and 14 and forcing it back into position in the clips.

The containers may be filled with oil if desired, or, rather partially filled; that is, to a certain extent, which would permit the telescoping movement in such position that the contacts are completed. The friction of the part 10 in the clip 12 is sufficient to 20 maintain the switch in open or closed position and hold the springs 22 under sufficient compression to compensate for slight variations as between the two containers of each pair and variations incident to temperature, 25 etc. In the event of any sparking or arcing, when the switch is opened or closed, the same is entirely inclosed in the containers and the damage and danger incident to the arcing is minimized. When a fuse is burned 30 out, it is also inclosed and protected in such a way that all damage or danger therefrom is obviated.

By making the part 11 of glass, the condition and position of the contact end of 35 the fuse wire may be observed and noted readily.

In the modified form of construction shown in Fig. 5, the parts 11 and 13 are essentially the same. In lieu of the form 40 of fuse wire and case therefor, another device is substituted as follows: A tubular case 25 is provided, preferably of glass, having secured on its ends by screw-threading caps 26 and 27, the former being a closed cap as 45 to its end and the latter a flanged cap. There is introduced in one end of the case 25 a tubular headed fuse receiver 28. The headed end of the fuse receiver 28 is held between the end of the case 25 and the flange 50 of the cap 27, and this receiver contains a fuse 29 which extends longitudinally through an opening therein and is provided with an enlargement at each end. The fuse 29 is substantially half the length of the 55 case 25, and the balance is occupied by a conducting spring 30, one end of which engages with the end of the fuse and the other end rests on the cap 26. When in closed position, the spring contact 22, similar to 60 22 before mentioned, will engage with the cap 26 to establish the circuit at this point. In case of excessive current the fuse 29 will be burned or blown out, which fact can be noted through the parts 10 and 25, when 65 these are both of glass, and by removing

the switch as before pointed out and removing the cap 13, the whole device, consisting of the containers 25 and the parts mounted thereon, can be bodily removed and a new one quickly substituted.

In the modified form of construction shown in Figs. 6, 7, and 8, spring clips 12^a—12^a and 14^a—14^a, similar to those heretofore described, are provided, except that the clips 14^a are not transversely slotted. 70 Mounted in these clips 12^a and 14^a respectively are longitudinally movable switch members consisting of a central tubular section 40 of insulating material and end sections 41 and 42 of conducting material, the former adapted to occupy a position within the clips 12^a or be displaced longitudinally therefrom, and the latter being considerably elongated with reference to the length of section 41 and in all positions of longitudinal 75 movement occupying a position in the clip 14^a. The end sections 41 and 42 are provided with plugs 43 and 43^a, respectively entering the ends of the part 40 and preferably 80 screw-threaded into the same. Introduced 85 between these plugs is a fuse wire 44 and a compensating and connecting spring 45, the two together establishing electrical connection between the section 41 on the one end and the section 42 on the other end. 90 The fuse 44 will preferably be received in a tubular casing 46 of insulating material, which will give support to the fuse wire, particularly in resisting the pressure of the 95 spring 45. When the switch is in open position, as shown in Fig. 6, the circuit is broken by reason of the metal section 41 being removed from the spring clip 12^a and the spring clip only finding bearing on the insulating tube 40. When moved to a position at the other limit of its movement, however, the section 41 becomes located in the spring clip 12^a and electrical connection is established through the parts described 100 to the spring clip 14^a. In this position the 105 parts are shown in Fig. 7. In like manner, as pointed out with reference to the previously described construction, the switch may be removed bodily from the spring clips 12^a and 14^a either while the switch is 110 in closed position or open position, and when so removed it can be dismantled and the fuse examined or replaced as occasion 115 may require. In this laterally described construction, the fuse is protected and supported in an effective manner and all trouble or accident from the fuse burning out is obviated and the parts may be readily dismantled for the replacing of a damaged fuse or otherwise. 120

It is evident that other modifications and variations in and from the construction herein described may be made without departing from the spirit of my invention, as defined in the appended claims. 130

What I claim as new and desire to secure by Letters Patent is:

1. A combined switch and safety-fuse comprising a pair of fixed members in circuit, a pair of members movable axially relatively to the first members and also in circuit, fuses, means for supporting said fuses, and means for engaging and disengaging said fuses during the axial movement of the members.
2. In a device of the character described, a pair of axially movable members, contacts associated therewith, means for maintaining the contact with one member, means for breaking contact with another member, and means for insulating said members.
3. In a device of the kind described, a pair of axially movable members, contacts associated therewith, means for maintaining the contact in one member, means for breaking the contact with another member, a fuse, a compensating contact with said fuse, and means for insulating said members.
4. A combined switch and safety-fuse, comprising longitudinally movable members for making and breaking a circuit, means for controlling the longitudinal movement, fuses, and means for yieldingly contacting with said fuses,
5. A combined switch and safety-fuse, comprising longitudinally movable members for making and breaking a circuit, means for controlling the longitudinal movement,

fuses, housings therefor, means for yieldingly contacting with said fuses, contacts 35 for said fuses, and means, whereby said fuses may be rejected from said contacts.

6. A combined switch and safety-fuse, comprising longitudinally movable members for making and breaking a circuit, means 40 for controlling the longitudinal movement, fuses, housings therefor, means for yieldingly contacting with said fuses, and contacts for said members.

7. A combined switch and safety-fuse, 45 comprising a pair of fixed members in circuit, a pair of members longitudinally movable relatively to the first named members and also in circuit, fuses, means for supporting said fuses, and means for engaging and 50 disengaging said fuses during the movement of the members.

8. In a device of the character described, a pair of longitudinally movable members, contacts associated therewith, means for 55 maintaining the contact with one member, means for breaking contact with another member, and means for insulating said members.

In witness whereof, I have affixed my signature, in presence of two witnesses, this 4 day of March 1908.

JAMES S. JOHNSTON.
